Marvin Deems

UNITED STATES PATENT OFFICE

PHILEMON LAROCHE, OF LAWRENCE, MASSACHUSETTS

DISPLAY DEVICE

Application filed March 2, 1928. Serial No. 258,501.

This invention relates to improvements in display devices and more particularly to devices which are adapted for use in advertising.

An object of this invention is to provide a device in the form of a dirigible airship and which may be attached to a kite or the like for display purposes at high altitudes.

A further object is to provide a display device of the class described above, which contains means for illuminating colored transparent discs positioned in the lower surface of the device.

Another object is to provide means for continuously rotating illuminating means for the colored discs so as to produce a striking color effect when viewed at a distance.

These and other objects are attained by the novel construction, combination and arrangement of parts, hereinafter described and shown in the accompanying drawing, constituting a material part of this disclosure, and in which:—

Figure 1 is a general view showing the toy attached to the lower part of a kite.

Figure 2 is a cross-sectional view of the display device.

Figure 3 is a cross-sectional view taken along line 3—3 of Figure 2.

Referring to the drawings, the display device, having a cigar-shaped body 6, is shown attached by the struts 5 to a part 4 of a kite. A realistic effect is produced by providing the device with wheels 7 and a propeller 8, which is rotated by the force of the wind upon its blades, the propeller being fixed to shaft 9.

Referring to Figure 2, it is seen that rotation of propeller 8 will cause shaft 9 to rotate, which in turn rotates gear 10, the latter being in mesh with gear 11 mounted on shaft 14. Also mounted on shaft 14 is a gear 12, which is in mesh with gear 13 fixed to shaft 15, the latter being journaled in partition 18 and having fixed to its outer end bevel gear 19, which is in mesh with bevel gear 20 mounted on shaft 21, the latter being vertically positioned, and having fixed thereto gear 22, which meshes with gear 23 fixed to shaft 24. Shaft 24 is journaled in partition 25 and carries at its lower end a collar 26, to which is

fixed a casing 31, which carries an electric lamp 35, as hereinafter described. A casing 30 is fixed to the surface 16 and is divided into a plurality of sections by partitions 29. The bottom of the casing is provided with apertures corresponding to the several sections and each aperture is covered by a disc of transparent colored material 27—28, such as glass, or celluloid, or the like, and the lower surface 16 of the device is provided with a plurality of apertures corresponding with the apertures in the casing 30, so that the transparent colored discs will be visible from below.

From the above description, it will be seen that when the propeller 8 is rotated by the wind, the casing 31, by virtue of the interconnecting gearing, will also be rotated so that the colored discs will be illuminated and be visible through the various apertures in the outer wall 16. In practice, the discs may be alternately colored red, green and yellow, or any other desired combinations, and the result of rotating casing 31 is to produce a changing color effect.

Inasmuch as it is necessary to illuminate the discs from the interior of the device, an electric lamp 35 is mounted in the socket 34, which is positioned in casing 31, the latter being supported by collars 26 and 32, which are attached to shaft 24. Two electrical conductors 37 and 38 lead from the lamp to brushes, which contact with rings 41 and 40, the latter being embedded in disc 39 made of insulating material, which is fixed to partition 33 and through which shaft 24 rotates. Also contacting with rings 40 and 41 are the insulated leads 42 and 43, which may be connected with the negative and positive poles of a dry cell 44, the latter being preferably of the flash light type. The lead 42 is connected to a switch 45, which enables the circuit to be controlled.

In operation, the device is attached to a kite or the like and thus raised to a considerable height above the ground. Previous to this, the switch 45 has been thrown so that members 42 and 43 will be connected with the negative and positive poles of the dry cell and thus cause the electric lamp 35 to light

and illuminate the discs 27. In the meantime, the rotation of propeller 8 by the wind causes casing 31 to rotate and as a result, the varied colored discs are illuminated in their consecutive order directly beneath the electric light, which will be visible through the discs.

The device herein described may be used effectively for advertising purposes, especially at night, on account of attracting the attention of persons on the ground by the changing colored lights.

Obviously, the parts of the device must be light in weight and a light metal, such as aluminum, is preferably used.

From the above description, it will be seen that a novel advertising device has been presented, which is simple in operation and inexpensive in construction and upkeep.

The foregoing disclosure is to be regarded as descriptive and illustrative only and not as restrictive or limitative of the invention, of which obviously an embodiment may be constructed, including many modifications, without departing from the general scope herein indicated and denoted in the appended claims.

Having thus described my invention, what I claim as new and desire to secure by Letters Patent, is:—

1. An aerial display device having a generally cigar shaped body and a propeller, a casing positioned in the bottom of said body and having a plurality of colored transparent discs mounted therein, means for illuminating said discs, and means connected with said propeller for rotating said illuminating means when the propeller is rotated by the wind.
2. An aerial display device comprising a body having an aperture in its lower surface, a propeller, a plurality of colored transparent discs positioned over said aperture and mounted on a stationary member, means within the body to illuminate said discs, and means connected with said propeller to rotate said illuminating means when the propeller is rotated.
3. A display device comprising a body having an aperture in its lower surface, a casing mounted in said body, said casing carrying a plurality of transparent colored discs positioned over said aperture, means to illuminate said discs, a propeller mounted on said body, gear connections between said illuminating means and propeller to rotate the illuminating means when the propeller is rotated.
4. In a display device having the shape of an airship having an opening in its bottom, and adapted to be attached to a kite, a propeller and a shaft therefor, a vertical shaft, a system of gears, connecting said propeller shaft and said vertical shaft to rotate the same upon the rotation of said propeller,

a casing attached to said vertical shaft to rotate therewith, an electric lamp in said casing, and a plurality of vari-colored transparent discs below said rotatable lamp casing to be illuminated in their consecutive order during the rotation of said lamp above the same for display purposes.

In witness whereof I have affixed my signature.

PHILEMON LAROCHE.
